UNITED STATES PATENT OFFICE.

LUTHER L. KENNEDY, OF BROOKLYN, NEW YORK, ASSIGNOR TO MERRANTHALER LINOTYPE COMPANY, A CORPORATION OF NEW YORK.

LINOTYPE-MACHINE.

SPECIFICATION forming part of Letters Patent No. 784,267, dated March 7, 1905.

Application filed September 1, 1904. Serial No. 222,998.

To all whom it may concern:

Be it known that I, LUTHER L. KENNEDY, of Brooklyn, county of Kings, and State of New York, have invented a new and useful Improvement in Linotype-Machines, of which the following is a specification.

This invention has reference to linotype-machines of the general character represented in Letters Patent of the United States No. 436,532. In these machines metal matrices representing individual characters are stored in a magazine, from which they are released one at a time in the order in which their characters are to appear in print, the matrices, together with expansible spacers, being delivered successively into an assembling mechanism wherein they are assembled or composed in lines, each line being thereafter presented momentarily to the face of a mold to form relief characters or type on the edge of a slug therein, after which the line is raised to the top of the machine and the individual matrices returned through a distributing mechanism to the magazine-channels from which they started. After the matrix-line is composed in the assembler the latter is raised for the purpose of presenting the line to a horizontal movable carrier by which the line is moved forward toward the mold.

It is of course necessary that the horizontal carrier shall return to its original or receiving position before a second line is presented thereto by the elevation of the assembler.

The object of the present invention is to prevent the operator from lifting the assembler and sending the composed line forward toward the casting mechanism unless it has been composed or "set out" to such length that it can be automatically justified by the spacing devices of the machine.

To this end it consists, essentially, of means for normally locking the assembling-elevator down, in combination with tripping or releasing devices connected with the assembling-slide, so that the assembler is unlocked and free to rise only when the assembler-slide is held forward by the presence of a full line of matrices therein. A tripping device is connected with the means for adjusting the

assembling mechanism to set lines of different lengths, so that the act of adjusting the machine for any given measure or length of line also effects the adjustment of the tripping device.

As all the other parts may be of ordinary construction, I have confined the drawings herein to those parts to which my invention is immediately related.

Figure 1 represents a front elevation of the assembling mechanism, the assembling-elevator, and adjacent parts. Fig. 2 is a horizontal section on the line 2 2, Fig. 1.

Referring to the drawings, H represents an inclined belt which receives the matrices successively from the magazine and delivers them downward over a guiding-surface to a position in front of a rotary star-wheel h³, by which they are pushed forward successively side by side into the horizontal channel or groove in the upper end of the assembling-elevator I. The matrices Z are sustained, as usual, in the elevator by horizontal shoulders therein.

As the composed line is increased in length by the addition of matrices and spacers thereto its advance is resisted, and it is held in compact form by the yielding finger or resistant J, carried by a horizontal slide j², guided in the main frame and known as the "assembler-slide." This slide is urged constantly to the right with moderate pressure by a spring or weight, as usual, and as it advances step by step it will be arrested and held until the composition of the line is completed by the usual brake or detent.

The machine is adjusted to set a line of predetermined length by means of a stop block or slide i³, mounted in a horizontal slot in the slide j and adjustably secured by a set-screw. When the line is of the predetermined length or of such approximation thereto as to forbid the insertion of the matrices for another word or syllable, the stop i³, which sounds an alarm-bell, as usual, encounters a fixed stop on the frame, thereby arresting the advance of resistant j, whereupon the delivery of matrices to the line is stopped preparatory to sending the line forward to the mold.

The assembling-elevator I is mounted, as usual, to slide vertically in the frame and connected with the manual or other operating devices, whereby on the completion of the line 5 the assembler is raised and the composed line carried upward between the depending arms of the transfer-carriage L L', which then moves horizontally to the left, carrying the line toward the mold. When the line is lifted 10 by the elevator, it is carried clear of the resistant J, and the assembler-slide immediately moves to the right, returning the finger J to a position near the star-wheel preparatory to the composition of the next line.

15 The foregoing parts correspond to those which bear like letters in Patent No. 436,532 and may be of the same or any equivalent construction.

My improvement is designed to prevent the 20 assembler I from being elevated to cause the transfer of the composed line until the line has acquired a length sufficient to insure its proper justification or elongation to the predetermined length by means of the ordinary wedge spacers or justifiers Y, forming part of the machine. For this purpose I provide an 25 automatic dog or lock M to hold the assembler down in its normal or receiving position. The locking device may be of any suitable construction, but is preferably made in the form 30 of a gravitating dog pivoted to the frame in position to directly engage the elevator, as shown. Whenever the elevator is lowered to the receiving position, this dog engages automatically to prevent it from being lifted.

For the purpose of disengaging the dog and 35 releasing the elevator when the line has acquired the proper length I mount in the assembler-slide j a longitudinal rod N, having one end connected directly or indirectly to the adjustable stop-block i¹³, and the opposite end in position to encounter the dog. This rod is carried forward with the assembler-slide as the matrix-line is elongated, and the parts 40 are so proportioned that when the line reaches the proper length the rod N will encounter the dog and push it out of engagement, thus leaving the elevator free to rise. When the elevator rises, the assembler-slide retreats to 45 the right, carrying with it the rod N and releasing the dog M, so that the assembler is automatically relocked when it is lowered. The assembler cannot be again elevated until the second line has reached the proper length, 50 when the dog will be disengaged as before.

Inasmuch as the tripping device is connected 55 to the stop i¹³, which controls the travel of the assembler-slide and the length of line composed, it follows that the adjustment of the 60 stop i¹³ to set the machine to any given length of line also serves to adjust the tripping device to correspond with the new measure or length of line. The essence of my invention in this regard consists particularly in combin-

ing with means for sending the composed line 65 forward, and adjustable devices for controlling the length of the line, intermediate connections whereby the adjustment of the machine to set a line of given length also adjusts the parts to prevent the line from being sent forward until it has acquired the proper length, and it will be manifest to the skilled mechanic that the parts may be widely varied in form and arrangement without departing from the method of operation herein described or passing beyond the limits of my invention.

In operating the machine the matrix-line first composed in the assembler is usually of less than the final length, justification by the wedge-spacers occurring after the composition is completed. This is because the line as composed is frequently of such length that the remaining space allotted will not admit the matrices for another word or syllable. The average space remaining to be filled for justification will depend to some extent on the final length or measure of the line and on the size of the type-faces and matrices employed. It is usual to set the stop device i¹³ to arrest the finger J before the matrix-line has reached the printing length or measure.

I prefer to connect the rod N adjustably with the stop i¹³, as shown in the drawings, or in any other suitable manner. In the construction shown the stop i¹³ is divided vertically 95 and its forward end j¹⁰ secured to the trip-rod N and adjustably connected to the main portion i¹³ by a flat spring j¹¹, having a series of perforations to receive the stud j¹² on the part i¹³. These connections admit of the rod being 100 set forward and backward in relation to the stop i¹³, so that the tripping action will occur sooner or later.

It will be understood that the adjustable connection between the rod N and the stop is not 105 of the essence of the invention and is not a necessary feature and also that any suitable adjustable connection may be employed.

The assembling-elevator, assembler-slide, and the means for delivering matrices there-to constitute jointly what is commonly known as the "composing" or "assembling" mechanism, while the adjustable stop for the assembler-slide is a means for determining the length of the composed line.

What I claim as my invention is—

1. In a linotype-machine, the combination of a matrix-assembling mechanism, adjustable means for determining the length of the composed line, and means connected with the latter to prevent the transfer of the composed line until it has acquired the predetermined length, whereby the adjustment of the machine for a line of any given length automatically effects the corresponding adjustment of the means for preventing the transfer of the line.
2. In a linotype-machine, the combination

of the assembling-elevator, a locking device therefor, the assembler-slide, an adjustable stop therefor, and a trip for the locking device connected with said stop.

5 3. In a linotype-machine, the assembling-elevator and means for delivering matrices thereto, in combination with a lock to prevent the movement of the elevator, the assembler-slide, an adjustable stop thereon, and a

connection from said stop to release the assembling-lock.

In testimony whereof I have hereunto set my hand, this 6th day of June, 1904, in the presence of two attesting witnesses.

LUTHER L. KENNEDY.
